UNITED STATES PATENT OFFICE.

CARL A. SODERLUND, OF BROOKLYN, NEW YORK.

ACTUATING DEVICE FOR THE THROW-OFF MECHANISM OF PRINTING-PRESSES.

1,359,442.

Specification of Letters Patent. Patented Nov. 16, 1920.

Application filed November 7, 1917. Serial No. 200,824.

To all whom it may concern:

Be it known that I, CARL A. SODERLUND, a citizen of the United States, residing at Brooklyn, in the county of Kings and State of New York, have invented new and useful 5 Improvements in Actuating Devices for the Throw-Off Mechanism of Printing-Presses, of which the following is a specification.

This invention relates to actuating devices for the throw-off mechanism of printing presses and seeks for its principal object to provide a device of this character which embodies a plurality of relatively adjustable sheet engaging devices whereby the same may be quickly applied and adjusted 10 with relation to the work.

Another object of the invention is the provision of a device of this character which embodies a plurality of alined rock shafts having secured thereto keepers which are adapted to coöperate with latches secured on the rock shaft to the throw-off mechanism, said shaft also being adapted to have adjustably mounted thereon sheet engaging devices, whereby upon improper feeding of 20 the sheets from the cylinder, the sheet engaging devices will cause the keepers to engage the latches and coöperate therewith to arrest motion of the rock shaft in order 25 to shut off further operation of the press.

A further object of the invention is the provision of an actuating device for the throw-off mechanism of printing machines comprising independently movable alined 30 rock shafts having relatively adjustable devices thereon under which the sheets are adapted to pass in their movement through the machine, and keepers adjustably secured to said shafts and adapted to coöperate with the throw-off mechanism to stop further operation of the press upon the improper feeding 35 of the sheet from the cylinder.

Another object of the invention is the provision of a device of this character which 40 is simple in construction, inexpensive to manufacture, and thoroughly reliable and efficient in operation.

With these and other objects in view, the invention resides in the novel construction, 45 combination and arrangements of parts fully described and pointed out in the following description and claims and illustrated in the accompanying drawings in which:—

50 Figure 1 is a fragmentary perspective view of the device showing a portion of the

rocking stop shaft of the throw-off mechanism.

Fig. 2 is a sectional view through the rock shaft and the keeper support. 60

Fig. 3 is a similar view through the rock shaft and the sheet engaging device support.

Fig. 4 is a sectional view on the line 4—4, of Fig. 3.

Fig. 5 is a sectional view on the line 5—5 65 of Fig. 1.

In printing presses or like machines which act upon sheets fed therethrough, certain mechanism is provided which is adapted to stop the machine and this mechanism usually includes a hollow rock shaft, such as shown in the drawings and substantially illustrated in the patent to Gustafson No. 912,562. No claim is laid to the stop mechanism which may be of any form employing 70 a rock shaft under which the sheets pass in their movement through the machine. 75

Referring to the drawings by characters of reference (A), designates the rocking stop shaft of a throw-off mechanism which 80 is provided with the usual latches, (B), clamped thereto by means of the bolts (C). The actuating device embodies a pair of alined rock shafts 10, mounted in the bearing arms 11, which are secured to the press 85 immediately beyond the cylinder. The shafts 10, are provided near their extremities with the abutment pins 12, which are adapted to contact with the pins 13, provided on the arms 11, in order to limit the 90 movement of the shaft 10, in one direction. The inner ends of the shaft 10, are received in the bearing 14, provided on an arm 15, which is secured to a convenient portion of the press and secured adjacent to the inner 95 ends of the shafts 10, on each side of the bearing 14, are the keeper supports 16, which are provided with openings 17, to receive the shafts. Set screws 18, are threaded into the keeper supports and are adapted to engage 100 the shafts 10, whereby the supports may be adjusted on the same. Keeper arms 19, are adapted to be received in the openings 20, provided in the supports 16, and are retained in place by means of set screws 21, 105 which are threaded into the support and adapted to enter the notches 22, in the keeper arms 19. The free extremity of the arms 19, are provided with down-turned portions 23, which are adapted to coöperate 110 with the latches (B), when the shaft 10, is rotated in one direction, whereby the rock-

ing stop shaft (A) will be arrested in its movement to throw-off the press. Adjustably arranged on the shaft 10 throughout the length of the same, is a plurality of supports 24, which are provided with transversely arranged openings 25, for the reception of the shafts 10. A set screw 26, is threaded into each support 24, and is adapted to engage the shaft 10, in order to retain the support in its adjusted relation thereto. The support is provided with an extended portion 27, which is provided with a square opening 28, for the reception of a similarly formed portion 29, on the detector arms 30. A notch 31, is provided in the portion 29, and is adapted to receive a locking portion 32, provided on the spring arm 33, which is attached to the upper face of the support 24, whereby the sheet engaging arms 30, may be detachably associated with the support. The inner extremity of the portion 29, is beveled as at 34, to admit of the easy insertion of the same within the opening.

In operation of the device, the detector arms 30 are primarily adjusted on the shafts 10 to admit of the normal feeding of the sheets thereunder during their movement through the press, this adjustment being accomplished by turning the supports 24 on the shafts 10 and securing them by advancing the set screws against said shafts. The keeper supports 16 are adjusted on the shafts so that the down-turned portion 23 of the arms 19 will be held in superposed relation to the latches (B), under the weight of the arms 30, the weight of which slightly overbalances the weight of the arms 19 and as heretofore set forth, the pins 12 and 13 serve to limit the movement of the shafts 10 whereby the arms 30 when properly adjusted will be arranged slightly above the sheets during their normal passage through the machine. Should the sheets buckle or become mutilated in a manner which would choke the machine, and continue to move therethrough, the arms 30 would be lifted, thereby lowering the down-turned portions 23 of the arm 19 into contact with the upper face of the latches (B) and upon the forward motion of the rock shaft, the portion 23 would spring down in rear of the latch, locking the same and arresting further motion of said shaft. Upon arresting the motion of the rock shaft (B) it will be understood that certain stopping mechanism is brought into play for cutting off further operation of the machine. By providing a plurality of alined rock shafts, it will be seen that the slightest defective feeding of a sheet thereunder will operate the throw-off mechanism, as the weight of only two engaging arms and the one rock shaft will necessarily be lifted. In some instances it has been found practical to run several

pieces of work through the machine simultaneously and by providing more than one rock shaft or a divided shaft, a plurality of detecting groups are had which will readily inform the operator of the machine which piece of work has caused the stoppage.

While I have shown and described a simple and preferred form of the invention, I desire to have it understood that such changes and alterations as fall within the scope of the appended claims, may be resorted to when necessary and that the showing is merely illustrative.

What is claimed as new is:—

1. The combination with a throw-off mechanism adapted to prevent operation of a printing press, of alined rock shafts, relatively adjustable devices thereon, under which the sheet is adapted to pass in its movement through the press, and keepers detachably secured to said shafts, and adapted to coöperate with said throw-off mechanism to arrest further operation of the press upon improper feeding of the sheets from the cylinder.

2. In a printing press of the character employing a rock shaft for the throw-off mechanism having latches thereon, the combination with the rock shaft, of movable keepers co-acting with said latches for preventing operation of said press, and independently operable groups of sheet actuated devices for transmitting motion to said keepers.

3. An actuating device for the throw-off mechanism of printing presses, comprising, a rock shaft, latches secured thereto, relatively adjustable independently movable groups of sheet engaging devices under which the sheets pass in their movement through the press, keepers adapted to co-act with said latches and means actuated by said devices for operatively moving said keepers relatively of said latches.

4. In a printing machine, the combination with a throw-off mechanism therefor, comprising a rock shaft, latches secured to the rock shaft, a plurality of detector groups, rocking shafts for each of said groups and a keeper secured to each of said rocking shafts adapted to co-act with one of the latches on the first mentioned rock shaft to arrest the motion of the same upon the improper feeding of the sheet under the detector groups whereby further operation of said machine is prevented.

5. The combination with stops adapted to control the throw-off mechanism of a printing press, of independently movable alined rock shafts, relatively adjustable detector arms arranged on said rock shafts under which the sheets pass in their movement through the machine and keepers adjustably secured to each rock shaft, said keepers adapted to coöperate with said stops to control said throw-off mechanism to cut off fur-

ther operation of the press upon improper passage of the sheets under the detector arms.

6. The combination with stop mechanism adapted to control the operation of a printing press, of independently movable rock shafts, means arranged on said rock shafts adapted to co-act with said stop mechanism, detector arms controlling said means and operable by the sheets passing thereunder, supports therefor movable throughout the length of and about the rock shaft, and means for securing the same with relation to the rock shaft.
- 15 7. The combination with stop mechanism adapted to control the operation of a printing press, of independently movable rock

shafts, means arranged on said rock shafts adapted to co-act with said stop mechanism, detector arms controlling said means and operable by the sheets passing thereunder, supports therefor movable throughout the length of and about the rock shaft, and means for securing the same with relation to the rock shaft, said supports provided 20 with sockets for the reception of said arms, a notch in said arms, an opening in said support, a resilient member secured to the support and provided with a locking portion extending into said opening for engagement 25 with the notch in the arm in order to secure the arms to said supports.

In testimony whereof I affix my signature.
CARL A. SODERLUND.
